PUMP CONSTRUCTION

Edwin G. Staude, Minneapolis, Minn.

Application June 6, 1932, Serial No. 615,622

6 Claims. (Cl. 103—126)

This invention relates generally to improvements in fluid pumps, and is particularly concerned with means for controlling pumping volume.

- 5 An important object is to provide mechanism for controlling the volume by controlling the pumping seal and to so control the seal as to progressively vary the pumping volume conformably to pumping requirements.
- 10 Another object is to provide a construction such that when the pump gears are idling, as for instance when no flow or pressure is required, the pump gears will be practically running in a bath of oil and consequently there will be little, if any, heat generated, whatever the speed of rotation of the pump gears.
- 15

This invention is related to the inventions of my copending applications for Power amplifying devices, respectively bearing Serial Numbers 20 615,621 filed June 9, 1932 and 615,620 filed June 6, 1932, now Patent No. 2,047,898, in that the present application relates to the pump structure per se, while the inventions of said copending applications relate partly to the manners of 25 controlling the pumping seals, with relation to other controlled mechanisms.

It is an important object of this invention to provide means wherein the "lag" or "delay" in starting, is entirely eliminated, due to the fact 30 that no vacuum is established in the fluid conveying passages of the pump. Tests have proved that in the practice of this invention, there is no "lag" or "delay" in the establishment of the pumping force, and it has been further 35 proved that the circulation pressure is reduced more than eighty per cent directly on motion of the volume control means in appropriate manner. Moreover, there is no noise whatever as the result of free flow of fluid around the pump 40 gears, and there is no heat whatever the velocity of the pump gears.

As exemplified in the above mentioned copending applications, the present invention finds valuable application in conjunction with auxiliary 45 power devices for automobiles in which the pump is constantly driven. Attempts have heretofore been made to obtain a reduction in volume by the use of a valve located on the intake side of the pump, but this device causes serious lag or 50 delay in pumping action due to creation of vacuum in the pump line, to which vacuum fluid must be supplied before full pumping pressure is available. Owing to the large volume of fluid in 55 continuous circulation at high car speeds, the amount of heat generated by these continuously

rotating gears has presented serious objections to the use of gear pumps. There is no limitation intended, however, by the statement that there is a nominal, continuous circulation maintained because an important feature is the use of an element which is movable with respect to the pumping means to instantly render such means inoperative or operative, or to progressively increase the pump volume, all in such manner as to conserve power, make for pumping efficiency 10 and avoid generation of heat.

An important feature of the invention relates to the construction for by-passing fluid at the meshing point of the pumping gears from the pressure side to the opposite side. Features of 15 the invention include all details of construction shown, along with the broader ideas of means inherent in the disclosure.

Other objects, features and advantages of the invention will appear from the description of the drawing forming a part of this application, and 20 in said drawing.

Figure 1 is a horizontal section on line 1—1 of Figure 2 through the intersecting pitch lines of 25 the pump gear, and shows the volume control in the open position;

Figure 2 is a vertical section on line 2—2 of Figure 1;

Figure 3 is a vertical transverse section on line 3—3 of Figure 2;

Figure 4 is a vertical transverse section on line 4—4 of Figure 1;

Figure 5 is an enlarged horizontal section of a portion of the volume control shown in Figure 1, with the control in closed position, or with the by-passage obstructed and the pump conditioned 35 for delivering fluid at the maximum pressure; and

Figure 6 is a detail vertical section taken on line 6—6 of Figure 2.

In the drawing, 62 generally indicates a pump case or block having a pair of pump gears 54 and 55. The pump gear 54 is mounted on the spindle 53 and is driven in any suitable manner from the clutch arrangement 52. The pump gear 55 revolves freely on a fixed shaft 56.

In order to enclose the face of the pump gears and close the ends of certain passages to be described, plate 57 is provided, which is securely bolted to the member 62 by bolts 60. The plate 50 57 has a groove 75 located at the intersecting pitch circles of the pump gears, and opening against said gears. Plunger 31 is slidable in a bore of the plate 51 and is adapted to operate 55 across, and to open or close the passage formed 65

by slot 75. The diameter of this plunger is somewhat larger than the width of the passage 75, and effectually shuts off the passage of the fluid through the passage when in the position 5 shown in Figure 5.

In this embodiment, the control member is about the size of a lead pencil or a little larger, say one-fourth of an inch in diameter and the area is about .049 of an inch. It will be understood that the end area of the element 37 may be equal to the area of the passage 75 and 37 may fit passage 75 as a piston.

While a cylindrical plunger has been shown, because that is the simplest form for making an oil tight sliding fit, there is no intention to limit the invention to the shape of the plunger, since it may be rectangular. Other constructions located in the side wall of the pump casing, as shown in Figure 6, which will permit the free 15 flow of fluid from the discharge side of the pump gears to the opposite side and permit throttling or controlling the seal, may be used.

The member 37 is controlled by an arm 34 which is slidable in slot 36 of an enlarged portion 38 of the control member 37. Due to this construction, the member 37 cannot rotate but can reciprocate, and the enlargement 38 acts as a stop against opposite walls of the casing or plate 57. In order to maintain the member 30 37 normally in the open position shown in Figures 1 and 2, a spring 40 is provided which is adjusted to the correct tension by a castle nut 41. A threaded plug 42 provides a bearing 43 for the control member 47, and also serves to 35 pocket the spring 40. A cap threaded on the corresponding threaded portion 45 of the plug 42 covers the end of the reciprocating member 37.

Referring to Figure 3 and assuming that the 40 device is used on an automobile, and that the plunger 37 is positioned as in Figure 5, when the automobile is moving forward, gear 54 is driven by shaft 53 in counter-clockwise direction, which sets up a fluid pressure in passage 45 64. Referring to Figure 1, the passage 64 is connected to passage 65 by a short passage 66. The passage 67 is connected to the passage 65 by a short passage 68. As pressure accumulates in the port 64 against the plunger 69 in passage 50 65, it forces it into the position shown in Figures 1 and 4 and thus uncovers the port 70, see Figure 4, which connects with the passage 71 leading into space 72 communicating with cylinder 29 to act against the piston 28.

55 When the pump gears 54 and 55 revolve in an opposite direction or clockwise, as for instance when the motor vehicle is backing, pressure accumulates in passage 67 and acts against the back of the plunger 69 causing it to move 60 to the opposite end of the passage 65 and establishing communication between passages 67, 68 and port 70, and passages 71 and space 72. It is, therefore, clear that whatever the direction 65 of rotation of the pump gear, effective fluid pressure against the piston 28 is always obtained.

Referring to Figure 3, the low pressure or intake side of the pump gears is the passage 73. This passage is connected by copper tubing 70 74 with a discharge of the oil purifier (not shown) now in common use on the engine of the conventional type of motor vehicle. The purpose is to provide for automatic replacement of fluid which has been lost through evaporation, 75 leakage, etc., and at the same time to provide

a sort of breather space through which gases or fumes may escape if developed as the result of friction due to long continued use, as for instance in the case where the device is used in a braking system during long continuous brake 5 application.

Assuming that the plunger 37 is in the position shown in Figure 5 and that pressure accumulates at 64, it will react laterally against the plunger 37. This might cause binding of the 10 plunger. To obviate this, flat surfaces 76 and 77 are provided, and these are connected with the slot 75 at each side of the plunger by crossing ducts or passages 78 and 79. When the 15 pressure accumulates at 64, the fluid will be 20 directed to the passage 78, see Figure 5, which is of equal area as the exposed surface of the plunger 37 in the passage 75, so that the lateral 25 pressure is equalized. If the pressure is reversed and accumulates at 67, the fluid flows 30 through the duct or passage 79 to the space 76 and acts as back pressure from the opposite side.

My invention includes the use of a "check" at the intersecting pitch circles of the pump gears located in the passage that connects the discharge side of the pump gear with the opposite side, which passage is located in the side wall of the pump case. The size of this passage and the size of the mechanism for checking the fluid depends upon the volume and capacity of 30 the pump.

It is possible, by the practice of this invention, to have the area of the plunger which is exposed to pressure be quite small, so that the 35 proportional back pressure on the plunger at five hundred or more pounds pump pressure per square inch, will only be nominal. The volume controlling member is balanced against pressure laterally. This construction permits accurate and instant control of the fluid with only a 40 nominal effort.

Since one is able to control the volume by the application of this invention to the ordinary type of pump gears, one can also proportionately control the velocity of the fluid, and, therefore, this 45 invention is particularly valuable where it is required that the revolution of the pump gears be continuous, because the pump can deliver fluid with full fluctuation from maximum volume and velocity to zero volume and velocity.

It is noted that this invention provides means moving independently of the pumping means for controlling the volume and/or seal, and also provides volume control means which, in the case of a gear pump, moves independently of the 55 pump gears; also the volume control means is operable in the wall of the pump.

I claim as my invention:

1. A gear pump comprising a walled casing having a pump chamber, meshing pump gears 60 in the chamber, a groove in the inner face of one of the walls and opposing the gears at their meshing point, and adapted to by-pass the pump fluid, a plunger reciprocable in the wall across the groove to control by-pass flow and having an end engageable with the side face of the gears to stop by-pass flow through the groove, a spring normally holding the plunger in a position to permit full fluid flow through the by-pass groove, and means for moving the plunger, against the action of said spring. 65

2. A gear pump comprising a walled casing having a pump chamber, meshing pump gears in the chamber, a groove in the inner face of one of the walls and opposing the gears at their 70 75

meshing point, and adapted to by-pass the pump fluid, a plunger reciprocable in the wall across the groove to control by-pass flow and having an end engageable with the side face of the gears 5 to stop by-pass flow through the groove, a spring normally holding the plunger in a position to permit full fluid flow through the by-pass groove, means for adjusting the tension of the spring and accessible at the outside of the pump casting, and means for moving the plunger, against the action of the spring.

3. A gear pump having a circulating system including a gear chamber having therein meshing pumping gears, a cover closing the chamber, 15 a groove in said cover opposed to the meshing point of the gears and adapted to by-pass the entire volume of fluid from the pressure and suction side of the system, a pumping pressure control plunger reciprocable in the cover and 20 traversing the groove to block passage of fluid therethrough and adapted to abut the gear faces at their meshing points, a swinging arm cooperating with the plunger for controlling it, a spring against the action of which the plunger is moved 25 to increase pumping pressure and adapted to normally move the plunger away from the gears, and means for adjusting the tension of the spring.

4. A circulating system including a gear pump having a casing and pump gears and having at 30 the meshing point of the gears a by-passage of sufficient size to by-pass the entire volume of the liquid around the gears from the pressure to the suction side, a piston plunger yieldable to the liquid pressure reciprocable across said passage toward and away from the side faces of 35 the gears to completely open and completely close the passage, yieldable means for holding the plunger to permit by-passage of all the pumped liquid, and means acting on the plunger

to forcibly and rapidly move it against the action of the last mentioned means to prevent any by-passing of liquid.

5. A circulating system including a gear pump having a casing and pump gears, and having at 5 the meshing point of the gears a by-passage of sufficient size to by-pass the entire volume of the liquid around the gears from the pressure to the suction side, a plunger reciprocable across said passage toward and away from the side 10 faces of the gears to completely open and completely close the passage, yieldable means for holding the plunger to permit by-passage of all the pumped liquid, means acting on the plunger to forcibly and rapidly move it against the action 15 of the last mentioned means to prevent any by-passing of liquid, and means limiting motions of the plunger in opposite directions respectively to permit full capacity by-passing and to prevent any by-passing.

6. A circulating system including a gear pump having a casing and pump gears, and having at 20 the meshing point of the gears a by-passage of sufficient size to by-pass the entire volume of the liquid around the gears from the pressure to 25 the suction side, a plunger reciprocable across said passage to completely open and completely close the passage, yieldable means for holding the plunger to permit by-passage of all the pumped liquid, means acting on the plunger 30 to forcibly and rapidly move it against the action of the last mentioned means to prevent any by-passing of liquid, said plunger having a flattened end engageable with the lateral faces of the gears at the meshing point, the said plunger 35 having a diameter greater than the depths of the gear teeth.

EDWIN G. STAUDE.
